UNITED STATES PATENT OFFICE.

JOHN HENRY LASKEY, OF BOSTON, MASSACHUSETTS.

SELF-LEVELING MARINE DINING-TABLE.

SPECIFICATION forming part of Letters Patent No. 604,831, dated May 31, 1898.

Application filed December 22, 1896. Renewed November 15, 1897. Serial No. 658,627. (No model.)

To all whom it may concern:

Be it known that I, JOHN HENRY LASKEY, a citizen of the United States, and a resident of Boston, in the county of Suffolk and State of Massachusetts, have invented certain new and useful Improvements in Self-Leveling Marine Dining-Tables, of which the following is a specification.

My invention relates to improvements in marine dining-tables, and has for its object to provide a simple and effective mechanism whereby the table and the people will always be level when the ship rolls, the table to be placed longitudinally in the ship's cabin.

15 The invention comprises a table pivoted longitudinally in the center on upright supports secured to the floor of the cabin and uprights connected with two shafts running longitudinally in the center of the table top 20 and bottom. The top shaft forms the pivot and the bottom one the supports for the chairs. From these uprights and at right angles to the shafts, at about ten inches from the floor of the cabin, there extend other shafts adapted 25 to support the platform for the feet of the people. The chairs are secured to the lower center shaft and are supported by a brace where they pass through the platform. On the deck is placed a shaft sliding in bearings 30 on either side of the center of the table, provided with a stiff spiral spring and resisting-collars secured to said shaft, a hole being made in the end of said shaft, in which is secured a rope that passes over a swiveled 35 block and is secured to the lower shaft. The object of this spring is to act as a counter-balance for a difference of two or three people more on one side of the table than on the other. I also provide a locking device where- 40 by I can lock the table so that the top will move with the deck, making it stationary.

The invention consists in certain features of construction and combination of parts, as will be hereinafter described and claimed. 45 Reference is to be had to the accompanying drawings, forming a part of this specification, in which similar figures of reference indicate corresponding parts in all the views.

Figure 1 is an elevation in section on line 50 $\alpha\alpha$. Fig. 2 is a detail side view of the locking mechanism. Fig. 3 is a detail side view

of the counterbalance mechanism. Fig. 4 is a side elevation of table.

In the said drawings, 10 represents the standards and main support upon which the 55 table swivels.

11 is the top of table, secured to the brackets 12.

13 are the upright shafts that connect the longitudinal shafts top and bottom. 60

16 are the cross-shafts that support the platform.

14 is the coupling that connects the cross-shafts 16 with the upright 13.

15 is the platform. 65

17 are braces secured to the platform and supporting the chairs.

18 is the seat-support secured to cap 19. Cap 19 is secured to shaft 20.

30 are the revolving seats mounted on supports 18. 70

36 is the deck.

23 is the friction-wheel.

Shafts 21, running longitudinally, form the pivots for the structure in bearings formed 75 on the top of the standard.

22 is a friction-band adjusted by screw 24, said band being held permanent and secured to upright 10. Shaft 20 extends longitudinally and is connected to shaft 21 by upright 80 shafts 13, on which are mounted caps 19, carrying seat-supports 18.

28 is a shaft that operates the locking device carried by brackets 29.

43 is a pulley secured to end of shaft 28, to 85 which is secured a rope 44, connected to levers 34. On the other end of shaft 28 is secured a lever 26 for operating the locking device.

27 is a quadrant provided with a notch to 90 receive the latch 45 on the lever.

When the lock-shaft 31 is withdrawn from the standard, the structure is free to move to the roll of the ship.

35 is a bracket secured to shaft 20, to which 95 crank or lever 34 is pivoted.

46 are the bearings through which shaft 31 slides, said shaft provided with a collar for resistance of spring 32.

33 is a link connection between shaft 31 and 100 lever 34.

37 is a shaft mounted on the deck and slid-

ing longitudinally in bearings 38, said shaft provided with a resisting-collar for spring 39. Shaft 37 is provided with a hole in the end to receive rope 45', passing through sheave 40 5 and secured to shaft 20.

41 is a bearing-block for sheave 40.

25 are the hand-rails running longitudinally through brackets 47, secured to table-top 11.

10 In my construction of a marine dining-table herein shown and described it will be evident that I have devised a simple and effective means whereby the table and the people always maintain a level position under all 15 circumstances, making it a luxury to dine on the ocean equal to dining on the land.

It will be evident that certain changes may be made in the mechanism of my table without departing from the scope of the invention, and hence I do not limit myself to the 20 exact details of construction and the arrangements of parts herein shown and described.

Having described my invention, what I claim as new, and desire to secure by Letters 25 Patent, is—

1. In a marine dining-table, the combination of a table, an upper horizontal shaft upon which it is mounted, a lower horizontal shaft and a seat-support mounted thereon, and provided with a seat, a foot-platform, a support for said platform and a connection between the upper and lower horizontal shafts, said table, seat and platform adapted to oscillate in unison and maintain positions relative to 35 each other.

2. In the construction of a marine dining-table, a frame structure composed of two longitudinal shafts connected by perpendicular shafts, a platform mounted on shafts running 40 at right angles and secured to the perpendicular shafts, and seats mounted on the lower longitudinal shaft; all pivoted on uprights, secured to the deck, substantially as shown and described.

45 3. In the construction of a marine dining-table, the combination of a frame structure pivoted on uprights secured to the deck, a locking device consisting of a shaft running longitudinally with the table and revoluble 50 in bearings mounted on the upper longitudinal shaft of the framework, a pulley secured to one end of said shaft and a lever and latch on the other end, a quadrant provided with

a notch to receive the latch, a rope on one end connected to the pulley and having the other end connected to the levers, said levers connected to the lock-shafts by links, and a spring mounted on said shaft to force them into the end standard, all mounted on the lower longitudinal shaft, substantially as 60 shown and described.

4. In a marine dining-table, the combination of a frame comprising uprights secured to the deck, and a horizontal shaft, about which it oscillates, and a means for counter-balancing said structure consisting of a shaft 65 slideable in bearings secured to the deck, a stiff spiral spring and resisting-collar on said shaft, a rope or connection from one end of said shaft and secured to the lower longitudinal shaft, and a swiveled pulley-block secured to the deck and through which the rope or connection passes.

5. In a marine dining-table, the combination with a stationary support or frame, and 75 a frame mounted therein and adapted to oscillate and comprising a table and a seat and seat-support connected and movable therewith, of means for locking the oscillating frame to the stationary frame, comprising a 80 spring-actuated shaft slideable in bearings and having an end to engage the stationary frame or support, a second shaft having an operating-lever and pulley, a rope or connection secured to said pulley, a bell-crank lever having an arm connected with the slideable shaft and the other arm connected with said rope, a quadrant fixed to the table-support and a latch to detachably engage the quadrant. 90

6. In a marine dining-table, the combination of the upper and lower horizontal shafts and the intermediate vertical upright, a table mounted on the upper shaft, a friction-wheel on said shaft, a friction-band surrounding 95 the wheel, the screw whereby the band is adjusted and the stationary support to which the band is secured.

In testimony that I claim the foregoing as my invention I have signed my name, in 100 presence of two witnesses, this 19th day of December, 1896.

JOHN HENRY LASKEY.
